UNITED STATES PATENT OFFICE.

WILLIAM H. DANIELS, OF SPRINGFIELD, ILLINOIS.

JOURNAL-LUBRICATOR.

No. 806,242.

Specification of Letters Patent.

Patented Dec. 5, 1905.

Application filed April 13, 1905. Serial No. 255,287.

To all whom it may concern:

Be it known that I, WILLIAM H. DANIELS, a citizen of the United States, residing at Springfield, county of Sangamon, and State of Illinois, have invented certain new and useful Improvements in Journal-Lubricators, of which the following is such a full, clear, and exact description as will enable others skilled in the art to which it appertains to 10 make and use my said invention.

My invention relates to lubricators of that class adapted to supply oil along the whole length of a journal and having an automatic feed controlling the oil-supply.

15 The purposes of my invention are to provide, in connection with a journal, means for supplying oil along the entire length of the journal, to provide a vibrating oil-cup easily attachable to car-axle boxes of the kind now 20 in common use, to provide means for controlling the oil-supply, to provide means for distributing the oil uniformly along the journal, and to provide means for removing gum or sediment from the journal.

25 With these ends in view my invention consists in the novel features of construction and combinations of parts shown in the annexed drawings, to which reference is hereby made, and hereinafter particularly described and 30 finally recited in the claims.

Referring to the drawings, in which similar numerals designate like parts in the several views, Figure 1 is a longitudinal section through a car-axle box embodying my improvements. Fig. 2 is a vertical transverse section, and Fig. 3 is a side elevation of the 35 scraper detached.

40 I have shown my improvements as applied to the axle-box of a railway-car axle; but they may without material modification and without departure from my invention be applied to other journals.

The car-axle box 1 is of the usual well-known form and has on its upper surface lugs 45 2, serving to connect the oil-cup with the box, as hereinafter explained. A hole 3 extends through the upper plate of the box and receives a downwardly-extending tube on the oil-cup.

50 The oil-cup 4 is preferably box-shaped and has a downwardly-extending tube 5, fitting loosely in the hole 3. It also has a forwardly-extending flange 6, fitting between the lugs 2, and a hinged door 7, through which oil is 55 supplied to the cup.

The tube 5 has a tapering bottom pierced

by a small hole 9, through which the oil flows. A ball 8 fits loosely in the tube 5. Brasses 11 lie on top of the journal 12, and the sides of the brasses are held in place by the 60 inner walls of the box, and the upper surface of the brasses are in contact with the under surface of the top of the box. The lower parts of the brasses are curved to conform to the journal, as shown. The upper parts of 65 the brasses are separated sufficiently to permit the scrapers 13 to slide freely between the brasses. The scrapers 13 are connected by a rod 14, having a suitable handle 15, and the lower parts of the scrapers are curved to 70 conform to the surface of the journal.

The rod 14 has a longitudinal channel 16, and in one of the blocks 13 is an inclined hole 17, communicating with the hole 9 in the tube 5 and the channel 16 in the rod 14. In 75 use oil flows through the holes 9 and 17 into the channel 16 and runs along the entire length of the channel, and when the channel is full the oil overflows along the length of the channel and falls on the upper surface of the journal. 80

When the rod 15 is in position with the hole 17 in registry with the hole 9, one end of the rod abuts against the inner wall of the box, and the handle 15 abuts against a downwardly-extending lug 19 in the box. 85 The rod springs sufficiently to permit the handle to pass the lug when inserting the scraper, and the lug prevents accidental longitudinal displacement of the scraper.

When the door 20 is open, the outer end of 90 the rod 14 may be sprung downward or to one side sufficiently to permit the handle 15 to pass the lug 19, and by pulling on the handle the scrapers may be slid longitudinally on the journal to scrape dirt or gum from the upper surface of the journal.

The oil-cup 4 being loosely connected with the box is kept in constant vibration by the vibration of the box, and the vibration of the cup vibrates the ball 8 in the tube 3, so as to 100 alternately raise the ball and permit it to fall or gravitate onto its seat, so that the ball serves as a means for controlling the supply of oil—that is to say, when the car is in motion there is constant vibration of the box 105 and the cup, causing similar vibration of the ball—so that when the ball rises oil flows under the ball and through the holes 9 and 17 into the channel 6. When the car stops, the vibration of the oil-cup also stops, and the 110 ball gravitates to close the hole 9 and shut off the supply of oil until the car again moves,

In attaching the oil-cup the pipe 5 is inserted in the hole 3, the flange 6 is placed between the lugs 2, and the rod 18 is placed in the holes in the lugs and above the flange 6 and connects the cup with the box, so that the cup may vibrate without becoming detached from the box.

The box 1 has a door 20 of the usual form.

The blocks 13 being connected by the rod 14 may be slid along on the journal by pulling on the handle 15.

The sliding of the blocks 13 on the journal serves to remove gum and grit from the journal.

Having fully described my invention, what I claim as new, and desire to secure by Letters Patent, is—

1. The combination of a box, a journal within said box, blocks slidable on said jour-

nal, a bar connecting said blocks and having a longitudinal oil-channel, and means for supplying oil to the channel of said bar.

2. The combination of a box, a vibratory oil-cup mounted on said box, a journal within said box, blocks mounted on said journal, a bar connecting said blocks and having a longitudinal channel, and a valve operated by the vibration of the oil-cup and controlling the supply of oil to the channel in the bar connecting said blocks.

In witness whereof I have hereunto subscribed my name, at Springfield, Illinois, this 4th day of April, 1905.

WILLIAM H. DANIELS.
